Franklin Bergart

United States Patent Office.

SAMUEL KEELER, OF LANCASTER, PENNSYLVANIA.

Letters Patent No. 63,056, dated March 19, 1867.

IMPROVEMENT IN SEED-DRILL TEETH.

The Schedule referred to in these Letters Patent and making part of the same.

TO ALL WHOM IT MAY CONCERN:

Be it known that I, SAMUEL KEELER, of the city of Lancaster, county of Lancaster, and State of Pennsylvania, have invented new and useful Improvements in the Teeth and Drag-Bar of Seed-Drills; and I do hereby declare the following to be an exact description thereof, reference being had to the accompanying drawings, and to the letters of reference marked thereon, making a part of this specification, in which—

Figure 1 represents a top view of the tooth and the drag-bar; and

Figure 2 a side view, the red lines showing how the tooth falls back when it has struck an obstruction.

The nature of my invention consists in the arrangement of the curved arm J, connected with the spiral spring M, that is located in the centre and operated between the sides of the drag-bar C, that I describe as follows:

A represents the ordinary-shaped seed-drill tooth; B is a single lug at top, to which the drag-bar C is attached by an iron bolt or pivot, D, the drag-bar C being made double, of two iron bars, the ends fitting on each side of the lug B, and the bolt D passing through the ends of the drag-bar, firmly connecting the drag-bar with the tooth. The drag-bar has three rivets, E F G, to strengthen the bars, with shoulders on the rivets to keep the bars an inch or two apart. The lower joint is formed of two lugs or, ears, H H, between which the connecting curved bar J operates on a bolt or pivot, K. This bar J has three or four holes at the outer end for the insertion of a wooden pin, L, and to regulate the proper inclination of the tooth to operate according to the character of the soil. The bar J being passed up above and between the drag-bars, the pin L is then inserted in the proper hole to shorten or lengthen the bar J, as may be required, and when the drill is in operation, and the tooth comes in contact with a stone, root, or stump, the pin L breaks and allows the tooth to fall back and pass over the obstruction without injury to the seed-drill. A new pin, L, is again inserted, and the drill is ready again for operation. M is a spiral spring, attached to the front of the curved arm J, passing over the rivet F, that may be made to play loosely as a roller, and operating in the centre and between the sides of the drag-bar C, the other end of the spiral spring being permanently fastened to the front rivet G, the spring allowing the tooth to pass over any obstruction, and enabling the tooth to keep its place, thus avoiding the use of the wooden pin L, that may therefore be dispensed with. The spiral spring M may be used uncovered, (as shown at figs. 1 and 2,) or enclosed in a cylindrical box, (as shown at fig. 3,) if deemed necessary.

What I claim as my invention, and desire to secure by Letters Patent, is—

The arrangement and combination of the curved arm J with the spiral spring M, operating as herein described and for the purposes set forth.

SAMUEL KEELER.
